Primary Examiner — Steven J Czyz*(74) Attorney, Agent, or Firm* — Dunlap Bennett & Ludwig, PLLC; Brendan E. Squire(57) **CLAIM**

The ornamental design for a first aid kit, as shown and described.

DESCRIPTION

FIG. 1 is a front perspective view of the first aid kit showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The honeycomb stippling in the drawings represent the appearance of a reflective material.

In the drawings, the evenly-spaced broken lines depict portions of the article that form no part of the claimed design; the dash-dot-dash lines represent the boundary of the claimed design and forms no part thereof.
